UNITED STATES PATENT OFFICE.

ALFRED SHACKLETON AND NILS RYERSEN, OF CHICAGO, ILLINOIS.

CARBURETOR.

Application filed September 27, 1920. Serial No. 413,024.

To all whom it may concern:

Be it known that we, ALFRED SHACKLETON and NILS RYERSEN, citizens of the United States, and residents of the city of Chicago, 5 in the county of Cook and State of Illinois, have invented certain new and useful Improvements in a Carburetor; and we do hereby declare that the following is a full, clear, and exact description of the same, reference being had to the accompanying drawings, and to the numerals of reference marked thereon, which form a part of this specification.

This invention relates to a carburetor, and 15 particularly to a carburetor wherein positively operated means are provided for controlling the admission of fuel and air in the proper ratios and quantities to afford an efficient explosive mixture. It is well known that there exist definite ratios in which fuel 20 and air should be mixed in the carburetor of an internal combustion engine in order that the same may operate in the most efficient manner.

25 Many attempts to accomplish this have resulted in complicated structures which have operated efficiently only under certain conditions of engine speed and load.

The present invention appertains to that 30 class of carburetors in which a mechanical movement connects the air control and the arrangement for controlling the supply of fuel so that a proper ratio between the two is maintained.

35 It is an important object of this invention to provide a carburetor having improved positively operated means for controlling the admission of fuel and air to form an efficient fuel mixture and having a non-restricted outlet passage for said fuel mixture.

40 It is another object of this invention to provide a carburetor having its parts so arranged that the instrument, as a whole, is long and narrow and has no projections extending very far sideways.

45 Other and further important objects of this invention will be apparent from the disclosures in the specification and the accompanying drawings.

The invention (in a preferred form) is

shown on the drawings and hereinafter more fully described.

On the drawings:

Figure 1 is a side elevation of a carburetor 55 embodying the principles of this invention.

Figure 2 is a top plan view of the same.

Figure 3 is an end elevation looking at the air inlet of the carburetor.

Figure 4 is a section on the line 4—4 of 60 Figure 2, with parts shown in elevation.

Figure 5 is a section on the line 5—5 of Figure 1.

Figure 6 is a section on the line 6—6 of Figure 4. 65

Figure 7 is a section on the line 7—7 of Figure 4.

Figure 8 is a slightly enlarged fragmentary section on the line 8—8 of Figure 4.

Figure 9 is an enlarged detail section 70 showing the fuel control means.

As shown on the drawings:

The carburetor of this invention comprises a unitary casing in which is formed a float chamber 1, a mixing chamber 2, an 75 air chamber 3, a mixture outlet passage 4, and an air inlet passage 5. Said air inlet passage 5 is adapted to be connected with any suitable source of air supply by means of a connection 6, while an apertured flange 80 7 is formed on the carburetor casing outside the mixture outlet for connection with the intake manifold of an engine on which the carburetor is mounted. Liquid fuel from a suitable source of supply is conducted into 85 the float chamber 1 through a connection 8 in the bottom thereof and a suitable float mechanism in said float chamber controls the flow of fuel from said passage 8 into the float chamber to maintain the fuel there- 90 in at a constant level in a manner which is well known in carburetor construction. Extending transversely of the carburetor casing between the mixing chamber 2 and the air chamber 3 is an integral member 9 in 95 which is centrally supported a passaged nozzle member 10, which is secured in position in said member 9 by a nut 11 engaged on a threaded portion on the lower end thereof. Said nut 11 engages the under side 100 of the member 9 and since an enlarged portion 12 of the tubular member 10 engages

the upper side thereof, the tightening of said nut 11 acts to secure said nozzle member 10 in position in the member 9. The liquid fuel is supplied from the float chamber 1 to a central passage 14 in said nozzle member 10 through a passage 13, which communicates with the float chamber and extends through the member 9 to a restricted passage 15 which extends transversely from the bottom of the passage 14. Said passage 14 extends upwardly through the member 10 and opens into a tubular passage which extends transversely through an enlarged portion 16 on the upper end of said member 10. To afford communication between the tubular passage in said member 16 and the mixing chamber 2 so that liquid fuel may be introduced into said mixing chamber, a tapered outlet nozzle passage 17, the smaller inner end of which communicates with said tubular passage, is provided.

Means are provided for governing the amount of liquid fuel introduced into the mixing chamber 2 through the nozzle outlet passage 17. For this purpose a shaft 18 is journaled in the transverse tubular passage in the enlarged portion 16 of the member 10, being positioned and secured therein by means of plates 19 and 20, which are secured to opposite faces of said enlarged portion 16. Said shaft 18, which is rotatably mounted in the tubular passage in the member 16 serves to entirely close the same and in order to provide regulable communication between the upper end of the passage 14 and the inner end of the nozzle outlet 17, a groove 21 is provided in said shaft 18 extending nearly around said shaft and, as shown in Figure 9, increasing in cross-sectional area as it extends around the shaft in a counterclockwise direction. Figure 9 shows the shaft 18 in such position that the smallest amount of liquid fuel is allowed to be drawn outwardly through the nozzle outlet passage 17. Since, however, the groove 21 in said shaft 18 increases in cross-sectional area as described heretofore, the rotation of said shaft 18 in a clockwise direction will serve to successively bring larger areas in said groove into effective position and thus allow larger amounts of liquid fuel to flow into the nozzle outlet passage 17 and outwardly therefrom.

Means are provided whereby said shaft 18 may be rotated from an outside source to control the amount of liquid fuel entering the mixing chamber 2. This rotation is effected by manually moving the rod 44 as explained below. A reduced portion 22 of the shaft 18 extends outwardly through the plate 20, through the carburetor casing, and is journaled in a boss 23 on the outside of said carburetor casing. Non-rotatably secured on the outer end of said reduced extension shaft 22 is a bevel pinion 24 which

meshes with a bevel gear 25 rotatably mounted on the upper end of a stub shaft 26 secured in the carburetor casing above the air inlet passage 5.

A mechanism is provided for regulating the amount of air entering the air chamber 3 to be mixed with liquid fuel in the mixing chamber 2 and said mechanism is interconnected with the means for regulating the fuel inlet in a manner which will be hereafter described. Mounted in the air inlet passage 5 in the carburetor casing is a casting 27 having a tapered passage 28 therein and having an integral member 29 extending transversely of said tapered passage at the end thereof adjacent the air chamber 3. Centrally supported in said transverse member 29 is a shaft 30 and mounted on said shaft 30 in the air inlet passage 5 is an enlarged extension 31 of said shaft 30 which abuts the outer side of the member 29 and has an enlargement 31^a formed on the outer end thereof. A nut 32 is engaged on a threaded portion of said shaft 30 which extends into the air chamber 3 and consequently a tightening of said nut will draw the end of the extension 31 against the transverse member 29 in the air inlet passage 5 and thus said extension 31 and shaft 30 will be held securely in axial position in the air inlet passage 5. For controlling the flow of air through the tapered passage 28, a valve 33 is slidably mounted on the extension 31 and said valve 33 is inter-connected with the operating mechanism for the shaft 22 and adapted to be manually controlled therewith in a manner which will now be described.

Pivots connected on each side of a sleeve 34 integral with and extending outwardly from said valve 33 are links 35, and the outer ends of said links 35 are in turn connected with the ends of a bifurcated member 36, the other end of which is non-rotatably secured to a shaft 37 which is pivoted transversely of the carburetor casing in a boss 38, as clearly shown in Figures 1, 2 and 4. A crank arm 39 is secured to the outer end of said shaft 37 and pivotally connected to the outer end of said crank arm is one end of a link 40, and the other end of said link 40 is pivotally connected to a vertically extending angle pin which is secured to a sleeve 42 mounted beneath and rotatable with the bevel gear 25. Thus it is apparent that a rotation of said sleeve 42 and the bevel gear 25 thereon causes a rotation of the reduced shaft 22 whereby the sleeve 18 is rotated and the supply of liquid fuel flowing outwardly from the passage 17 is increased or diminished, and also causes a rocking of the bifurcated member 36 about the shaft 37 whereby the air valve 33 is moved inwardly or outwardly along the sleeve 31 to increase or diminish the amount

of air entering the carburetor through the tapered passage 28 in the casing 27. In order that this rotation of the sleeve 42 may be manually effected, a vertically extending angle pin 43 similar to the angle pin 41 is secured to said sleeve opposite said angle pin 41 and pivotally connected to said pin 43 is a rod 44, which connects the sleeve 42 to a suitable manual actuating means such as a foot or hand throttle lever. To facilitate carburation and the starting of the engine on which the carburetor is mounted, especially during cold weather, an electric heating element 45 is provided. Said heating element 45 is positioned in the air chamber 3, as clearly shown in Figure 4, and is adapted to be connected with a suitable source of electric energy, such as a storage battery, by means of insulated terminals 46 and 47 leading outwardly therefrom through a plug 48, which is removably secured in the carburetor casing in the floor of the air inlet chamber 3.

The operation is as follows:

As heretofore described, liquid fuel enters the passage 14 in the tubular nozzle 10 through a restricted passage 15, which communicates with a passage 13 in the member 9 leading into the bottom of the carburetor float chamber. When the engine on which the carburetor is mounted is idling, the shaft 18 is in such a position that the groove 21 therein is in the position shown in Figures 6 and 9 and consequently a limited amount of fuel is introduced into the mixing chamber 2. The proper amount of air to be mixed with the fuel introduced during idling is received in said mixing chamber from the air chamber 3, having entered said air inlet chamber around the edges of the slideable air valve 33 which is in closed position when the engine is idling. When it is desired to increase the speed of the engine a pull is exerted on the rod 44 whereby the sleeve 42 is rotated and the rotation thereof is transmitted to the shaft 18 through the bevel gear 25 and the bevel pinion 24 in the reduced shaft 22. This rotation of the shaft 18 is in a clockwise direction and acts to bring a larger cross-sectional area of the groove 21 therein into effective position to afford communication between the fuel passage 14 and the nozzle outlet passage 17. Simultaneously with the rotation of said shaft 18, the rotation of the sleeve 42 is transmitted to the link 40 and acts to rock the shaft 37 through the crank arm 39 whereby the lower end of the bifurcated member 36 on said shaft 37 is moved outwardly and the air valve 32 which is connected thereto by the links 35 is also moved outwardly allowing additional air to enter the air chamber through the tapered passage 28.

It is thus apparent that due to the simul-

taneous regulation of the amount of fuel and air which are allowed to enter the mixing chamber 2, it is possible to introduce at all times into said mixing chamber the proper proportion of air and fuel to afford an efficient combustible mixture. Since this ratio is not a constant one the proper compensation is provided by the particular construction of the groove 21, by the tapered air passage 28 in the casing 27 and by the ratio between the bevel gear 25 and the bevel pinion 24. The relation between these three variable regulating means is so arranged that with the opening of the throttle, i. e., with the rotation of the sleeve 42, sufficient quantities of fuel and air are supplied to the mixing chamber 2 to afford at all times the proper amount of a fuel mixture to operate the engine on which the carburetor is mounted at the highest efficiency.

We are aware that numerous details of construction may be varied through a wide range without departing from the principles of this invention, and we therefore do not purpose limiting the patent granted otherwise than necessitated by the prior art.

We claim as our invention:

1. In a carburetor, a mixing chamber, means for admitting air thereto, an upright standard in said chamber having a cavity therein, a fuel supply conduit leading to said standard, a fuel duct leading through said standard from said conduit to said cavity, a round plug occupying said cavity, said plug having a groove therearound in position to register with said duct, the bottom of said groove forming a spiral concentric with said plug, a lug in said groove between the shallowest and deepest parts thereof contacting with the wall of said cavity, and a fuel outlet leading from said cavity to the top of said upright, whereby rotating the plug through nearly a complete revolution will change the delivery capacity of the standard from one extreme to the other.

2. In a carburetor, a mixing chamber, means for admitting air thereto, an upright nozzle in said chamber spaced away from the walls thereof, and a grooved shaft journaled in the nozzle transverse thereto for controlling the flow of fuel therethrough, said shaft also having a bearing in a wall of the mixing chamber.

3. In a carburetor, a mixing chamber, means admitting air thereto, an upright nozzle in the middle of said chamber, a float chamber, connections from said float chamber to the bottom of said nozzle, a valve rotatable about a horizontal axis located in said nozzle near the top thereof and controlling the flow from said float chamber into said mixing chamber, and a horizontal shaft extending through the wall

of the mixing chamber and operating said valve.

4. In a carburetor, a vertical mixing chamber, a horizontal air inlet, an air chamber connecting said air inlet and mixing chamber, a slideable air controlling valve between said air inlet and said air chamber, a rotatable fuel controlling valve in said mixing chamber, and mechanism connecting said valves for simultaneous operation, said mechanism including a vertical

stub shaft rotatably mounted on the air inlet wall, and a horizontal shaft journalled in the wall of the mixing chamber.

In testimony whereof we have hereunto subscribed our names in the presence of two 15 subscribing witnesses.
